UNITED STATES PATENT OFFICE.

CECIL L. SAUNDERS, OF CLEVELAND, OHIO.

PNEUMATIC COTTON-GIN.

1,280,863.

Specification of Letters Patent.

Patented Oct. 8, 1918.

Application filed November 13, 1913. Serial No. 800,783.

To all whom it may concern:

Be it known that I, CECIL L. SAUNDERS, a citizen of the United States, residing at Cleveland, in the county of Cuyahoga and

5 State of Ohio, have invented certain new and useful Improvements in Pneumatic Cotton-Gins, of which the following is a specification.

My invention relates to a cotton-gin in which the separation of the seeds from the fibers is effected by a combination of pneumatic and mechanical devices. My device is an improvement on the type of machine shown in U. S. Patent No. 849,141, granted 15 to Story B. Ladd April 2, 1907, in which a perforated roller is provided with means for holding, by suction, the fibers on its surface, while the seeds are held from rotation with the cylinder by means of a fixed knife-blade; and in which the fibers held by suction to the surface of the cylinder, are carried partially around the circumference of the cylinder and then blown off by a blast of air.

25 The present invention relates to an improved apparatus for obtaining a more complete removal of the fiber from the seeds and comprises means for positively moving the seeds with reference to the surface of the 30 suction roller; means for assisting such removal by means of suction; means for removing the lint or fiber from the surface of the suction roller without undue twisting or tangling of the fiber; and also to other features which will appear from the following specification and claims.

The present invention also includes a seed-board or grating applicable not only to the suction-roller type of gin, but to saw-gins, 40 this seed-board or grating having arranged in connection therewith a pneumatic suction or blast which tends to force the seeds through the grating, and also to deliver them to a conduit through which they are conveyed to any suitable place of collection.

In the accompanying drawings:

Figure 1 is a longitudinal section through the machine;

Fig. 2 is a transverse section through the 50 hopper;

Figs. 3 and 4 are details illustrating the construction of various forms of cylinder surfaces.

Fig. 5 is a longitudinal section of a modified form of machine;

Fig. 6 is a transverse section through the machine illustrated in Fig. 5;

Fig. 7 is a detail of the stripping-knife; and

Figs. 8 and 9 are details showing the arrangements of the perforations in the suction cylinder.

Referring to the drawings, A is a perforated metal drum journaled in standards 1, 2 and provided with a belt pulley 3. 65 Mounted above the drum is a series of hoppers B. Extending into the bottom of the hoppers and adjacent to the exterior portion of the drum A is a screw-conveyer C, enclosed in a casing D extending laterally 70 from the hopper. Partitions L may be arranged as shown, and cause the seed to be extruded through openings L', though these partitions may be omitted, as pointed out hereinafter.

75 Protruding into the space between the conveyer-casing and the drum is an adjustable knife-blade or knocker E which extends the entire length of the conveyer. The conveyer is mounted on a shaft 4 driven in any 80 suitable manner. Mounted on brackets 5, 6 carried by standards 1, 2 is a stationary division drum F having suitable partitions to divide the interior of drum A into four sections, I, II, III, IV. Section I is connected 85 by conduit G to a suction fan. Section II, through a conduit H, is connected to a stronger suction device than that used for section I, and section III, through conduit J, is connected to a still more powerful suc- 90 tion. Section IV is connected by conduit K to a blast pump.

The drum-surfaces corresponding to each suction section are covered with material suitable for the work to be performed. Thus, 95 the surface of section I is preferably covered with a layer 10 of rubber or walrus hide perforated to correspond to the perforations in the drum A. The second section of the drum A is roughened on its outer surface, either by roughening the surfaces of the drum itself (see Fig. 3) or by providing a coating 12 of rubber, leather, walrus hide or other like material which is roughened. The third section is covered with a coating 100 105 of rubber, leather, walrus hide or other like material, provided with teats or projections with intermediate perforations, corresponding to those in the drum, which teats will be engaged by the blades of the conveyer and 110

the end of the knocker-blade E, as shown in Fig. 2.

The material blown off from the several sections is collected in the several conduits 5 13, 14, 15.

As shown in Figs. 2 and 6, the division drum F may be provided with oppositely-directed extensions 20, 21, carrying flaps of leather or suitable material to limit the action 10 of the suction or blast to the desired portions of the drum and to prevent leakage from the blast to the suction chamber.

In order to insure a proper distribution of the blast, adjustable partitions P, P, P, P 15 may be inserted in the blast chamber to direct the proper volume of air into each conduit.

The operation of the device is as follows: The cotton to be cleaned is delivered into

20 the hopper B, and passes downward between the conveyer blades until it reaches the perforated surface of the drum. The light suction at this point holds the fibers while the seeds are carried by the rotation 25 of the drum against the knocker blade E and are at the same time moved longitudinally by the blades of the conveyer. The fibers are held both by frictional and pneumatic engagement by the suction of the drum, so that most of the long fiber is removed 30 from the seeds carried around by the drum and blown off by the blast into the conduit 15. The seeds, with some lint still adhering to them, may be carried by the 35 conveyer, when partitions L are omitted, from section T onto the roughened surface of section II and are there subjected to the action of a stronger suction; a similar operation being effected with still stronger suction 40 on section III, where the teats bent over by the action of the conveyer blades and knocker blade, entangle any remaining lint, which is blown off the drum by the blast into the appropriate conduit 13.

45 As the result of the continued frictional and suctional holding of the fibers and the forcible movement of the seeds by the conveyer blades, the fibers are pulled off from the seeds in a particularly effective manner. 50 By the combined action of the rotating drum and the longitudinal movement produced by the conveyer, the material is rapidly and continuously removed from the hopper, thereby providing a machine of large capacity.

The seeds fed along the upper surface of the perforated drum by the conveyer are delivered through openings L' into any suitable receptacle.

60 While I have described the apparatus as comprising a perforated cylinder, it will be apparent that any perforated surface such as that of a moving belt or rotating disk, may similarly be provided, at different portions 65 of its surface, with different characters

of covering, which covering may be provided with teeth, bristles, pins or teats to assist the adhering-hold of the fiber or lint to the surface, and it will also be apparent that the various suctions may be varied to suit the 70 particular condition of the material being acted on, in the course of its progress along or across the perforated moving surface from section to section.

It is further apparent that the relative 75 positions of the parts can be reversed, that is, the conveyer may be located within the cylinder and the suctions on the outside.

While I have described the drum as provided with three distinct characters of surface, the entire drum may be provided with only one such prepared surface, and the relative arrangement of these surfaces may be varied to suit the particular conditions.

A modified form of apparatus is shown in 85 Figs. 5 and 6, in which there is arranged within the feed hopper a distributing roller or evener 30 provided with a plurality of projecting pins 31, the pins being arranged, if desired, in spiral rows. The ends of the 90 pins are arranged in such proximity to the suction roller A that they will positively remove the seeds from the adjustable knife-blade or knocker E'. The casing 32 of the feed hopper has a grating 33 at one side 95 thereof to permit seeds and other materials separated from the cotton to pass therethrough. I also provide a grating 34 in close proximity to the knife E' through which grating the separated seeds may pass. 100 Beneath the grating is a seed conduit 35 and also a blast chamber 36. This blast chamber has at the end near the grating an opening or series of openings having their orifices directed in such a manner as 105 to cause a suction through the grating 34 and thus facilitate the passage of the seeds through the grating into the seed conduit 35. A passage 37 may connect the blast chamber and seed conduit or the seed conduit 110 may have a separate blast supply to deliver the seed therefrom to any suitable place of collection. The individual bars of the grating may be hollow and provided with slots on their lower sides so that when they 115 are connected to the blast supply, the inwardly directed draft will further assist to pull the seeds through the grating 34.

This means of removing seeds is applicable not only to the particular pneumatic gin of 120 this application, but to the seed boards of the ordinary saw and roller gins.

38 is a mote-board which serves to direct away from the cylinder any motes or other material which are found on the outer layer 125 of the lint held by the suction to the perforated roll A. 39 is a rubber stripping roll which moves the lint from the suction roll and delivers it to the belt 40.

Fig. 7 shows a stripper knife E² having 130

a corrugated or waved edge, which is of advantage in that a glancing instead of a direct blow is given to the stripper knife.

The feeding cylinder and its coöperating revolving perforated cylinder may be mounted each on a horizontal axis; and when so mounted they may be arranged side by side or they may be mounted, either one above the other. The two cylinders may also be mounted each on a vertical axis, or on axes slightly inclined to the vertical, and these upright positions are advantageous in that they permit the seeds to be somewhat more readily removed.

15 The operation of this form of device, like that of the form shown in Figs. 1 and 2, depends upon the retention by the suction through the perforated cylinder of the lint fibers on the surface of the cylinder while the seeds are separated from the fibers by the action of the seed knife. In the present form of device, the seeds as they are pushed away from the surface of the cylinder are subjected to the suction produced by the air blast into the seed conduit, this suction being of material assistance in securing the prompt and rapid removal of the seeds from the edge of the stripper knife or knocker E'. Any seeds which may pass the grating 34

30 are carried around by the revolving pins 31 and may pass out through the supplementary grating 33.

It will be understood that the suction into the perforated cylinder A tends to hold the seeds on the edge of the stripper knife E' but that by the mechanical action of the pins 31 and the combined force of gravity and the suction into the seed conduit, this tendency is overcome.

40 While I have shown only one feed hopper and stripper knife E' associated with the perforated cylinder, I may use several of these agencies associated with the same cylinder, this use of several stripping devices being particularly facilitated by the arrangement of the rolls with their axes vertical.

The lint or fiber sucked onto the perforated cylinder is advantageously removed by the stripping roller 39 which may be longitudinally corrugated, without the use of an outwardly-directed blast from the inside of the roller, although such a blast may also be used if desired. By the use of the roller, the fibers which have been drawn out into parallel lines are removed without material alteration of this parallelism, a feature of much importance, as thereby the fibers are, in subsequent milling operations, more readily carded. As shown in Fig. 6, the blast chamber is retained within the perforated cylinder, as this blast serves to clean the perforations.

The arrangement of the perforations in the cylinder A in the manner shown in Figs.

8 or 9, *i. e.* with longitudinal rows of perforations with therebetween a longitudinal imperforated space, is of advantage in that the temporary removal of suction as the unperforated surface of the cylinder passes the stripper knife, facilitates removal of the seeds, and the diagonal arrangement of the openings, whether in the slot form of Fig. 8 or the hole form of Fig. 9 serves, as has been found in practice, to lay the fibers in a more parallel direction than would otherwise be the case.

While I have shown a single cylinder with means of producing varying suctions from section to section, the same purpose will be accomplished by a number of cylinders each having its specially prepared surface and necessary suction, the material being passed from one cylinder to next.

I claim:—

1. A cotton-gin comprising a perforated drum, a hopper located near one end of the drum, a screw-conveyer extending the length of and arranged in working proximity to the perforated drum and into the hopper, 90 and a knife-blade located adjacent the drum and conveyer for separating the cotton-seed from the fiber, and means for producing a suction through the drum.

2. A cotton gin comprising a perforated drum, means for producing different degrees of suction along said drum, a hopper located near one end of the drum, a screw-conveyer extending the length of and arranged in working proximity to the perforated drum 100 and into the hopper, and a knife-blade located adjacent the drum and conveyer for separating the cotton-seed from the fiber, and means for producing a suction through the drum.

3. A cotton-gin comprising a perforated drum having its peripheral surface divided into sections the surfaces of which sections have different degrees of adherence for cotton fibers, and means for providing suctions of different strength for each section.

4. A cotton-gin comprising a perforated drum having its peripheral surface divided into sections the surfaces of which sections have different degrees of adherence for cotton fibers, and means for providing suctions of different strength for each section, a hopper located near the drum, a screw-conveyer extending the length of the perforated drum and into the hopper, and a knife-blade located adjacent the drum and conveyer for separating the cotton-seed from the fiber, and means for producing a suction through the drum.

5. In a cotton-gin, a perforated suction cylinder, means for removing the seeds, and a mote-board out of contact with said cylinder and in position to disengage the motes from a layer of fiber on said cylinder.

6. A cotton-gin comprising a series of per-

forated drums, the surfaces of which have different degrees of adherence for cotton fibers and means for providing suctions of different strength for each drum, hoppers 5 extending the length of the perforated drums and provided with seed-removing means, knife-blades located adjacent the drums to separate the seed from the fiber, gratings adjacent the seed knives, a conduit

beneath the gratings, and means for producing a current of air through the gratings and in the conduits. ¹⁰

In testimony whereof I affix my signature in presence of two witnesses.

CECIL L. SAUNDERS.
